UNITED STATES PATENT OFFICE.

GEORGE P. BOSWORTH, OF PAWTUCKET, RHODE ISLAND, ASSIGNOR OF ONE HALF TO JOHN B. GRAY, OF SAME PLACE.

STOP-MOTION FOR SPOOLING-MACHINES.

SPECIFICATION forming part of Letters Patent No. 350,033, dated September 28, 1886.
Application filed April 12, 1886. Serial No. 198,635. (No model.)

To all whom it may concern:

Be it known that I, GEORGE P. BOSWORTH, of Pawtucket, in the county of Providence and State of Rhode Island, have invented a new and useful Improvement in Stop-Motions for Spooling-Machines, of which the following is a specification.

My invention consists in the combination of a frictional disk or cap provided with catch-spurs with the spindle and its spool-revolving disk or cup and the drop-wire mechanism of a spooling-machine, as hereinafter fully set forth.

Figure 1 is a transverse section of a portion of a spooling-machine, in which the frictional disk or cap is shown in section. Fig. 2 is a view of the under side of the frictional disk or cap. Fig. 3 is an edge view of the same, broken away to show the construction of the frictional surfaces. Fig. 4 is an enlarged side elevation of the stop-lever and drop-wires, and the pivot-stand for holding the same for attachment to the bolster-rail. Fig. 5 is a plan view of the same. Fig. 6 is a vertical section taken in the line $\alpha\alpha$ of Fig. 5. Fig. 7 is a side elevation of the drop-wire removed from its pivot-stand. Fig. 8 is a side elevation of the stop-lever. Fig. 9 is an end view of the same.

In the accompanying drawings, Fig. 1, A is a portion of the frame of the spooler; B, the step-rail; C, the bolster-rail, and D the spindle. Upon the spindle D is secured the circular disk or cup E, adapted to support the spool F, and to impart motion to the same, and between the cup E and the spool F, and loosely upon the spindle D, is placed the frictional cap G, which is preferably made of "struck-up" sheet metal, and is provided with a central perforation, a , adapted to receive the upper portion of the spindle. To the lower side of the cap G is secured the friction-disk b, made of rubber or other suitable material, which may be cemented or otherwise attached to the metallic portion c; and to the upper side of the cap G is secured a similar frictional disk, d, which comes in contact with the bottom of the spool, while the lower attached disk, b, comes in contact with the upper surface of the disk or cup E. The cap G is provided with the downwardly-extending catch-spurs e e, which serve to engage with the stop-lever f

upon the breaking of a single thread, thus stopping the rotation of the cap G, and also of the spool F, which rests upon the friction-disk d of the cap. The several threads m pass upward from their bobbins through guide-eyes g at the outer edge of the box H, and over the friction-bar I, thence through the eyes of the drop-wires h, and upward over the loose roller i, thence downward through the eye j of the wave-motion bar J onto the spool F. When the several threads being wound upon the spool are in perfect condition, the drop-wires will be held up, so that the stop-lever f will be held below the plane of the revolution of the catch-spurs e e of the cap G. When upon the breaking of one of the several threads the lever f is caused to rise into engagement with one of the catch-spurs e, the flange k of the cap G will serve to prevent the end of the lever f from bearing against the lower side of the continuously-revolving cup E of the spindle. The drop-wires h h and lever f are of ordinary well-known construction—such as are used in other spooling-machines—and are pivoted to a stand, M, which is secured by screws to the bolster-rail C. The engaging end of the stop-lever f is held loosely between the side guides, m m, and said lever is provided at its lower side with the lateral arms n n', against which the downwardly-projecting spurs o of the pivot-heads N of the drop-wires h rest when the drop-wires are unsupported by the threads.

The drawing, Fig. 9, shows the lateral arms n n' as adapted for three drop-wires, two of the same being located on one side of the stop-lever f, and one on the other side, as shown in the plan view, Fig. 5. The engaging end of the stop lever f is made to overbalance the opposite end of the same, so that when the drop-wires are raised by the thread to the position shown in Fig. 6 the stop-lever f will be inclined downward, so that the point of the same will not engage with the catch-spurs e e of the cap G; but upon the breaking of any one of the several threads the drop-wire for that thread will fall, and its spur O, coming in contact with the lateral arm n or n', as the case may be, will cause the stop-lever f to rise to engagement with the catch-spurs e to stop the spool. The drop-wires h h and the stop-lever f are all held loosely on the pivot-wire p. It is to

be understood that the downward flange *k* may be dispensed with, and in that case, if so desired, a fixed stop may be provided to prevent the lever *f* from bearing against the lower side 5 of the revolving disk or cup *E*; and it is evident that the catch-spurs *e* may be made to extend outward horizontally; but the construction shown and described is that preferred by me. The friction-disks *b* and *d* may also be held loosely with the disk or cap *G*, instead of being attached thereto.

I claim as my invention—

1. The friction disk or cap, which is provided with a central perforation adapted to 15 loosely fit the spindle, the opposite frictional

disks, and the catch-spurs, substantially as described.

2. The combination of the spindle, provided with the spool-revolving disk or cup and the stop-lever and drop-wires, with the disk or cap 20 arranged loosely upon the spindle at the upper side of the spool-revolving disk or cup, and provided with upper and lower frictional surfaces, and with projecting catch-spurs adapted for engagement with the stop-lever, 25 substantially as described.

GEORGE P. BOSWORTH.
